TYPEWRITER WARNING DEVICE

David B. Brannen, Tucson, Ariz.

Application September 27, 1949, Serial No. 118,081

3 Claims. (Cl. 197—189)

1

The present invention relates to a signalling device for typewriters, and more particularly to a mechanism or device for indicating when the end of a sheet of paper has been reached.

In using a typewriter it is difficult to determine when the end of a sheet of paper is approached so as to maintain on all sheets a generally uniform margin as the lower edge of the sheet is hidden behind the platen of the machine.

Devices have heretofore been provided to overcome this difficulty and, in many instances, have not been wholly satisfactory because of the complexity of their design and because only a limited movement of the parts thereof is possible necessitating excessive pressure on the paper causing slight groove lines on its surface or lines on the carbon copies. In other devices adjustments are required which are sometimes difficult and generally time consuming to make.

The present invention aims to overcome the difficulties and disadvantages of prior constructions by providing a device which is simple and economical in manufacture, efficient in operation and durable in use.

It is an object of the present invention to provide a signalling device which remains in adjustment regardless of the size or thickness of the paper with which it is used.

Another object of the invention is to provide a device operable by paper of any width which may be used with the typewriter in which the device is installed.

These objects are accomplished by providing a device having an operating member positioned in the path of the paper typed and restrained from producing a warning signal until the end of the paper is reached at which time the operating member is released to actuate the signal.

A construction in accordance with the invention is advantageous in that a comparatively long moment arm is had for the paper engaging member thereby lessening the unit pressure on the paper and minimizing the possibility of marring its smooth surface. Further, in applicant's construction the pressure of the moment arm is applied to the paper at the rear of the last sheet.

Other objects and advantages of the invention will be apparent from the following description and from the accompanying drawings which show, by way of example, an embodiment of the invention.

In the drawings:

Figure 1 is a sectional view taken along the line of 1—1 of Figure 3 and showing the mechanism in accordance with the invention in place

on a typewriter and with a piece of paper inserted in position so that the device is ready to produce a warning signal upon the approach of the end of the paper.

2 Figure 2 is a view corresponding to Figure 1 but with the paper removed and the mechanism in the position assumed after the warning signal has been given.

Figure 3 is a rear elevational view of a typewriter equipped with the mechanism.

Figure 4 is a top view of the paper guide of the typewriter showing the slot or opening for the paper engaging member.

Referring to the drawings there is shown in 15 Figure 1 a mechanism in accordance with the invention in position on a typewriter 1 (Figures 1 and 3) having a platen 2 and a paper guide 3. The mechanism comprises a paper engaging lever or feeler 4 pivotally carried by a rod 5 and having an operating extension or striker rod 6 tipped by a striker or clapper 7 to actuate a warning signal bell or gong 8.

The typewriter 1 may be of any standard construction and usually includes a carriage frame 10 carrying on its front edge a guideway 11 secured in position by a screw member 12. A slide member 14 is supported by the guideway 11 and has an upwardly turned resilient arm 15 rotatably supporting a roller 16. A line space lever 17 is mounted at one end of the carriage 10 for the platen. At the rear edge of the carriage frame 10 is carried a bolt 19 supporting the warning signal bell 8.

The platen 2 is also of standard construction 35 and has, as usual, a supporting shaft 20 rotatably arranged in the carriage frame 10. The outer surface of the platen 2 has a semi-resilient covering 21, and the ends of the rod 20 are fitted with knobs 22.

40 The paper guide 3 is utilized for guiding the paper around the lower side of the platen 2 and may be of any design serving the purpose. As shown, the paper guide 3 extends the length, and is curved about, the lower portion of the diameter of the platen 2 although it does not necessarily extend the entire length of the platen. At the rear of the platen the paper guide has slots 24 and 25 to receive rollers 26 and 27 which are rotatably carried on a shaft 29 and resiliently urged against the platen 2 by springs 30 and 31. The shaft 29 is journaled by suitable bearing means 32 and 33. The paper is held against the front side of the platen 2 by a front roller 36 having a shaft 37 carried by bearing means 38. An opening or slot 39 is made in the paper

guide 3 for the feeler 4, and if necessary, the slot is also made in the carriage frame 10 as indicated at 39a to provide clearance for the rocking movement of the feeler. A scale 40 is attached by screw means 41 to downwardly turned and apertured lugs 3a of the front edge of the paper guide 3.

The paper guide is apertured as indicated at 42 to receive screws 42a. The area around the apertures is slightly recessed so that ends of the screws 42a will not interfere with paper entering the machine. When several sheets of paper are inserted in the typewriter, the entire paper guide 3 pivots slightly in a counter-clockwise direction about the screws 42a, thus providing the necessary clearance between the roller 36 and the platen 2.

The paper engaging lever feeler 4 may have any desired width and is attached to the rod or shaft 5 by any suitable means such as by brazing 43 and the feeler is pointed in the direction of travel of the platen 2. Preferably the paper engaging lever is thin and formed with a tapered outer edge, the feeler being curved slightly upwardly along its length to conform to the shape of the platen 2. On the opposite side of the rod 5 is attached an extension 44 apertured to receive a bolt 45 having an outwardly extending end 46. The striker rod 6 is attached to the extension 44 by the screw 45. Preferably the striker rod 6 is of semi-resilient construction so when actuated by a sudden movement the clapper 7 at its outer end is snapped against the bell 8 to produce a clear warning signal. In order that the feeler 4 normally may be held away from the platen 2, resilient means are used to swing the rod 5 in the counter-clockwise direction and preferably an apertured flat spring 49 is used for this purpose being secured to the carriage frame 10 by suitable means such as the screw member 50. The free end of the spring 49 is adapted to abut against the outwardly extending end 46 of the bolt 45 to counteract the weight of the clapper 7 and hold the feeler 4 away from the platen 2.

When assembled in position on a typewriter the signalling device is always ready for operation and requires no pre-setting or other adjustment. In operating a typewriter equipped with the signalling device a sheet of paper 51 is inserted as usual at the rear of the typewriter between the platen 2 and the paper guide 3. The platen 2 is rotated and the paper is drawn downwardly behind the platen and is held against the platen surface by the rollers 26 and 27. As the platen is rotated the front edge of the paper passes between the rod 5 and the paper guide 3 contacting the paper engaging lever or feeler 4 and moving it upwardly toward the platen 2 thereby opposing the action of the spring 49 and moving the clapper 7 away from the bell 8. As the platen is further rotated, such as during progressive lines of typing, the bottom edge of the paper is moved around under the platen and finally past the end of the feeler 4. The feeler 4 is then released and resiliently urged in the counter-clockwise direction under the action of the spring 49, swinging the striker 6 to contact the clapper 7 against the bell 8 to produce the warning signal. By reason of the semi-flexible construction of the striker rod 6 a snapping action is had of the clapper which produces a clear warning signal.

It is thus apparent that the present invention provides a signalling device which is simple in

construction and may be operable by paper of any width that may be used in the typewriter in which the device is installed. By reason of the positioning of the feeler at approximately the center of the platen 2 no difficulty is had in positioning the paper in the typewriter so that the signal will be given irrespective of the width of the paper.

While the invention has been described and illustrated with reference to a specific embodiment thereof, it will be understood that other embodiments may be resorted to without departing from the invention. Therefore, the form of the invention set out above should be considered as illustrative and not as limiting the scope of the following claims.

I claim:

1. In a typewriter having a carriage frame, a platen and first and second paper guide rollers, a paper page end warning device comprising a warning bell, a paper engaging lever having an end directed towards the forward side of the platen, a mounting rod supported by the carriage frame for the paper engaging lever, actuating means for the warning bell responsive to movement of the paper engaging lever, and a paper guide having a slot in juxtaposition to the end of the paper engaging lever, the paper guide being turned away from the platen to provide a recess therewith in tangential alignment with the direction of the paper as it passes between the platen and the first paper guide roller, the mounting rod being interposed between the paper guide and the platen at a position between the recess and the second paper guide roller so that the paper is guided outside the rod away from the platen and tensioned between said rod and said paper guide roller to urge the paper engaging lever end out of the slot, the paper engaging lever being thereafter released by the end of the paper to reenter the slot to actuate the warning bell.

2. In a typewriter having a carriage frame, a platen and first and second paper guide rollers, a paper page end warning device comprising a warning bell, a paper engaging lever having an end directed towards the forward side of the platen, a mounting rod supported by the carriage frame for the paper engaging lever, the rod having its axis parallel to the axis of the platen, the paper engaging lever being positioned at approximately the center of the axial length of the platen, actuating means for the warning bell responsive to movement of the paper engaging lever, and a paper guide having a slot in juxtaposition to the end of the paper engaging lever, the paper guide being turned away from the platen to provide a recess therewith in tangential alignment with the direction of the paper as it passes between the platen and the first paper guide roller, the mounting rod being interposed between the paper guide and the platen at a position between the recess and the second paper guide roller so that the paper is guided outside the rod away from the platen and tensioned between said rod and said paper guide roller to urge the paper engaging lever end out of the slot, the paper engaging lever being thereafter released by the end of the paper to reenter the slot to actuate the warning bell.

3. In a typewriter having a carriage frame, a platen and first and second paper guide rollers, a paper page end warning device comprising a warning bell, a thin flat paper engaging lever having an end directed towards the forward side

of the platen, a mounting rod supported by the carriage frame for the paper engaging lever, spring means to urge the paper engaging lever away from the platen, the rod having its axis parallel to the axis of the platen, the paper engaging lever being positioned at approximately the center of the axial length of the platen, actuating means for the warning bell responsive to movement of the paper engaging lever, and a paper guide having a slot in juxtaposition to the end of the paper engaging lever, the paper guide being turned away from the platen to provide a recess therewith in tangential alignment with the direction of the paper as it passes between the platen and the first paper guide roller, the mounting rod being interposed between the paper guide and the platen at a position between the recess and the second paper guide roller so that the paper is guided outside the rod away from the platen and tensioned between said rod and

said paper guide roller to urge the paper engaging lever end out of the slot, the paper engaging lever thereafter released by the end of the paper to reenter the slot to actuate the warning bell.

DAVID B. BRANNEN.
